Primary Examiner—Douglas D. Watts*Attorney, Agent, or Firm*—Charles W. Almer[57] **ABSTRACT**

The present invention features a disposable razor unit having a razor head which is detachable from the handle. According to the preferred embodiment of the present invention, the handle has attachment means which consists of three prongs which extend outward from the handle. The center prong has a tooth on the underside of the end opposite the handle. The razor head has a chamber which receives the attachment means of the handle when the razor head and the handle are coupled. The chamber has a clearance slot and a locking shoulder at its innermost, central point into which the tooth of the middle prong fits to fasten the razor head and handle together. The fit between the handle and the razor head is such that the razor head may be removed by a forward force exerted on the top of the chamber by the user, however the fit is sufficient that the handle and the razor head will not become separated by normal forces encountered during shaving.

FIG-1

FIG-2

FIG-3

FIG-4

FIG-5

FIG-6

DISPOSABLE RAZOR WITH REMOVABLE RAZOR HEAD

The present invention relates to disposable razors and in particular to disposable razors having removable razor heads.

BACKGROUND OF THE INVENTION

Disposable razors currently account for a large percentage of total razor usage worldwide. Typical currently available disposable razors are razors in which the razor head, containing the blade or blades, and the razor handle are permanently fastened together to form a single piece. Such razors are designed to remain effective for a certain number of uses and, once the blades become dulled, are to be discarded in their entirety. Prime advantages to the user of disposable razors are price and convenience. Because disposable razors are designed to be discarded after a certain number of uses, they are constructed of materials less expensive than those used in non-disposable razors designed for permanent use. A disadvantage of disposable razors is that disposal of the entire unit, i.e. the small razor head and the large handle, adds to the environmental burden of already cluttered landfills. In order to solve environmental problems associated with cluttered landfills, worldwide reduction of the amount of disposable products being produced is necessary. The present invention will provide a means to aid in controlling worldwide environmental problems resulting from excess disposable products.

It would, therefore, be desirable to provide a disposable razor wherein the razor unit did not have to be discarded in its entirety when the blade became dulled. A razor unit having the desirable qualities of a disposable razor but having a removable and replaceable razor head would greatly reduce the environmental problems associated with disposable razors. Such a razor unit would allow the razor head portion, which is typically much smaller than the handle portion, to be discarded when the blade became dulled, while the larger handle portion could be re-used a number of times before being eventually discarded. In other words, the larger handle portion would be discarded less frequently than the smaller razor head, thereby reducing the amount of frequently disposable material. It would further be desirable to provide such a disposable razor wherein the razor head may be easily removed from the razor handle by a force exerted on the top surface of the razor head. The removal of the razor head in such a manner would result in a safer razor in that the user would engage the surface of the razor head opposite the blade edge in order to remove the razor head. Other means of removal may also be employed.

SUMMARY OF THE INVENTION

The present invention features a disposable razor unit having a razor head which is detachable from the handle. According to the preferred embodiment of the present invention, the handle has attachment means which consist of three independent, resilient prongs extending outward from the handle. The center prong incorporates a triangular tooth on the underside of the end opposite the handle. A chamber is positioned in the razor head to receive the attachment means of the handle when the razor head and handle are coupled. The chamber has a clearance slot and locking shoulder at its innermost, central point into which the tooth of the middle prong snap fits to fasten the razor head and handle together for use. The tooth on the center prong springs upward as the prong is inserted into the chamber and

snaps downward onto the locking shoulder upon engagement through the clearance slot to provide sufficient interference to hold the razor head in place.

The resilient prongs also provide the mechanism for the release of the razor head from the handle. The fit between the handle and the razor head is such that a finger force exerted on the top side of the razor head by the user changes the relationship of the resilient prongs with the locking shoulder and slot, and eliminates the interference which holds the razor head in place. In normal use, the fit between the razor head and the handle is sufficient so that the handle and the razor head will not become separated by normal forces encountered during shaving.

BRIEF DESCRIPTION OF THE DRAWINGS

FIG. 1 is a perspective view of the razor of the invention.

FIG. 2 is a perspective view of the razor of the present invention with the razor head separated from the handle.

FIG. 3 is a top view of the attachment means of the present invention.

FIG. 4 is a cross-sectional view in the plane of the line 4—4 of FIG. 1 in which the tooth is engaged with the locking shoulder.

FIG. 5 is a cross-sectional view in the plane of the line 4—4 of FIG. 1 with the tooth disengaged from the locking shoulder.

FIG. 6 is a cross-sectional view in the plane of the line 4—4 of FIG. 1 with the razor head separated from the handle.

DETAILED DESCRIPTION

The embodiments of the present invention are designed to provide a disposable razor which has a removable razor head. As used herein, the term "razor head" is meant to include disposable cartridges designed for separate attachment to a razor handle, as well as the operative portion of a razor wherein the operative cutting portion is integrally formed with the handle portion. According to the present invention, razors comprised of disposable materials are disclosed which provide a removable razor head which may be separated from the razor handle by exerting a forward finger force on the top of the razor head.

The preferred embodiment of the present invention is illustrated in FIG. 1. This embodiment comprises a disposable handle 10 and a removable razor head 11 which are fastened together. The embodiment illustrated in FIG. 1 is designed for two blades. Those skilled in the art will appreciate that the handle and razor head may be of various configurations, i.e., the razor head may contain one or more blades. Preferably, razor head 11 and handle 10 are designed for non-permanent use, i.e., they are intended to be disposed of separately after a certain number of uses.

FIG. 2 illustrates the preferred means for attaching the handle and the razor head. In the preferred embodiment, three independent, resilient prongs 12, 13, 14 extend outward from the end of the handle 10 to be attached to the razor head 11. Chamber 15 is positioned on razor head 11 in a manner so that prongs 12, 13, 14 may be inserted into the chamber during fastening and are enclosed within chamber 15 when the razor unit is fastened together.

FIG. 3 illustrates the top of the three independent, resilient prongs 12, 13, 14 of the preferred embodiment of the present invention. The two end prongs 12, 14 have tabs 19 which extend inward toward the central prong 13. Open areas 25 are created between each prong so that each prong may move independently of the other prongs.

FIGS. 4 and 5 illustrate a cross-section of the attachment means of the present invention. FIG. 4 illustrates the razor head 11 and handle 10 fastened together in the preferred manner by prongs 12, 13, 14 which are enclosed within the chamber 15. Center prong 13 has a tooth 16 located on its underside at the end furthest from the handle. Clearance slot 17, located in the innermost central point of chamber 15, is large enough to accommodate tooth 16. Locking shoulder 18 is provided on the underside of chamber 15, adjacent to the clearance slot 17. Perhaps as best illustrated in FIG. 5, the preferred at rest alignment of center prong 13, shown in cross section, is lower than that of end prongs 12, 14. When the entire unit is fastened together, center prong 13 retains its lower at rest alignment when tooth 16 is snap fit within clearance slot 17. In such position, the unit is securely fastened together by an interference fit between tooth 16 fitting within clearance slot 17 and thereby engaging locking shoulder 18 in the razor head 11. When the unit is so fastened together via tooth 16, clearance slot 17 and locking shoulder 18, the razor head 11 will not move independently of the handle 10 in response to forces encountered during shaving.

As illustrated in FIG. 5, razor head 11 and handle 10 may be separated by the exertion of force F on the top, outer side of chamber 15, i.e., on the surface of the razor head opposite to blades 20, 21. Force F can vary widely, but preferably is within the range of 0.5 to 15 pounds. Such force causes center prong 13 to deform from its at rest alignment and raise so that tooth 16 disengages from clearance slot 17 and locking shoulder 18 and eliminates the interference fit. The removal of the interference allows the handle 10 to be separated from the razor head 11. The removal of the razor head in such a manner is safe for the user in that the user's hand contacts the portion of razor head 11 opposite to blades 20, 21, thus reducing the chance of injury from the blades.

Similarly, during attachment of the razor head and the handle, center prong 13 is deformed upward as prongs 12, 13, 14 are inserted into chamber 15. Center prong 13 returns to its lower at rest alignment upon engagement of tooth 16 with clearance slot 17 and locking shoulder 18 in order to attach the razor head and the handle together.

According to an alternative embodiment of the present invention, a shaving aid is incorporated into the razor head of the present invention. It will be appreciated by those skilled in the art that the shaving aid can be incorporated by several different methods including attaching or embedding the shaving aid to a portion of the razor head.

Exemplary materials constituting the shaving aid may comprise one or various combinations of the following:

- A. A lubricating agent for reducing the frictional forces between the razor head and the skin, e.g., a microencapsulated silicone oil.
- B. An agent which reduces the drag between the razor parts and the skin, e.g., a polyethylene oxide in the range of molecular weights between 100,000 and 600,000; a non-ionic polyacrylamide; and/or a natural polysaccharide derived from plant materials such as "guar gum".
- C. An agent which modifies the chemical structure of the hair to allow the razor blade to pass through the whiskers very easily, e.g., a depilatory agent is one example.
- D. A cleaning agent which allows whiskers and skin debris to be washed more easily from the razor parts during shaving, e.g., a silicone polyethylene oxide block copolymer and detergent such as sodium lauryl sulphate.

- E. A medicinal agent for killing bacteria, or repairing skin damage and abrasions.
- F. A cosmetic agent for softening, smoothing, conditioning or improving the skin.
- G. A blood coagulant for the suppression of the bleeding that occurs from nicks and cuts.
- H. An essential oil such as menthol.

As has been mentioned hereinabove, the configuration of the shaving aid, its place of application to the razor head, the manner of attachment and/or other means and method of incorporation may vary widely to fit particular requirements.

While there have been described what are presently believed to be the preferred embodiments of the invention, those skilled in the art will realize that various changes and modifications may be made to the invention without departing from the spirit of the invention, and it is intended to claim all such changes and modifications as fall within the scope of the invention.

I claim:

1. A disposable razor unit comprising:
a handle;
a reusable attachment means located on one end of said handle; and
a cartridge including at least one blade and having receiving means for receiving said attachment means, said cartridge including a substantially flat bottom surface extending along a plane, said receiving means extending downwardly below said plane of said bottom surface;
wherein said cartridge is removably attached to said handle and wherein said reusable attachment means comprises a plurality of resilient, independently movable prongs which extend outwardly from said one end of said handle.
2. The disposable razor unit of claim 1, wherein said plurality of prongs comprise two end prongs and one center prong, each of said prongs having an at rest alignment.
3. The disposable razor unit of claim 2, wherein the at rest alignment of said center prong is lower than the at rest alignment of said two end prongs.
4. The disposable razor unit of claim 3, wherein said receiving means comprise a chamber.
5. The disposable razor unit of claim 4, wherein one of said plurality of prongs has a tooth and said chamber has means for receiving said tooth upon insertion of said cartridge and handle into said chamber.
6. The disposable razor unit of claim 5, wherein said tooth is positioned on said center prong.
7. The disposable razor unit of claim 6, wherein said means for receiving said tooth comprise a clearance slot and a locking shoulder.
8. The disposable unit of claim 1, wherein said cartridge may be removed from said handle by exerting force in a direction away from said handle.
9. The disposable razor unit of claim 8, wherein said force required to remove said cartridge is within the range of 0.5 to 15 pounds.
10. The disposable unit of claim 1, wherein said cartridge comprises a razor head having a shaving aid arranged thereon.
11. A razor unit comprising:
a handle;
at least one prong located on one end of said handle; and
a disposable cartridge including at least one blade and having a top surface where blade edges are exposed and

a substantially flat bottom surface extending along a plane, said cartridge further including a mounting chamber extending downwardly away from said plane of said bottom surface, said chamber being sized and shaped to receive said at least one prong of said handle for mounting of said cartridge on said handle, wherein said cartridge is removably attached to said handle and wherein said at least one prong comprises a plurality of prongs. 5

12. The razor unit of claim 11, wherein said disposable cartridge may be removed from said handle upon exertion of an external force on said cartridge in a direction away from said handle. 10

13. The razor unit of claim 11, wherein said force required to remove said disposable cartridge from said handle is within the range of 0.5 to 15 pounds. 15

14. The razor unit of claim 11, wherein said cartridge comprises a razor head having a shaving aid arranged thereon. 20

15. A razor unit comprising:

a handle including an extension member located at one end thereof; and 25
a disposable cartridge adapted to be removably attached to said handle by a user, said disposable cartridge including at least one blade and having a top surface where blade edges are exposed and a substantially flat bottom surface extending along a plane, said cartridge further including a mounting chamber extending downwardly away from said plane of said bottom surface and defining a single opening adapted to receive said extension member therein to accommodate removable mounting of said cartridge on said handle wherein said handle includes a plurality of extension members located at one end thereof. 30

16. The razor unit of claim 15, wherein said disposable cartridge may be removed from said handle upon exertion of an external force on said cartridge in a direction away from said handle. 35

17. The razor unit of claim 16, wherein said force required to remove said disposable cartridge from said handle is within the range of 0.5 to 15 pounds. 40

18. The razor unit of claim 15, wherein said cartridge comprises a razor head having a shaving aid arranged thereon. 45

19. A razor unit comprising:

a handle including a plurality of extension members located at one end thereof, at least one of said extension members extending to a greater height than at least one other of said extension members; and 50

a disposable cartridge adapted to be removably attached to said handle by a user, said disposable cartridge

including at least one blade having a top surface where blade edges are exposed and a substantially flat bottom surface extending along a plane, said cartridge further including a mounting chamber extending downwardly away from said plane of said bottom surface and defining a single opening, said plurality of extension members being operatively arranged within said opening to accommodate removable mounting of said cartridge on said handle. 5

20. The razor unit of claim 19, wherein said disposable cartridge may be removed from said handle upon exertion of an external force on said cartridge in direction away from said handle. 10

21. The razor unit of claim 20, wherein said force required to remove said disposable cartridge from said handle is within the range of 0.5 to 15 pounds. 15

22. The razor unit of claim 19, wherein said cartridge comprises a razor head having a shaving aid arranged thereon. 20

23. A razor unit comprising:

a handle including a plurality of extension members located at one end thereof; and 25
a disposable cartridge adapted to be removably attached to said handle by a user, said disposable cartridge including at least one blade having a top surface where blade edges are exposed and a substantially flat bottom surface extending along a plane, said cartridge further including a mounting chamber extending downwardly away from said plane of said bottom surface and defining a single opening therein, at least one of said plurality of extension members being operatively arranged within said mounting chamber to release said disposable cartridge from its assembled position on said handle. 30

24. The razor unit of claim 23 wherein a pair of extension members cooperate to provide said mechanism for releasing said disposable cartridge from assembled position on said handle. 35

25. The razor unit of claim 23, wherein said disposable cartridge may be removed from said handle upon exertion of an external force on said cartridge in direction away from said handle. 40

26. The razor unit of claim 25, wherein said force required to remove said disposable cartridge from said handle is within the range of 0.5 to 15 pounds. 45

27. The razor unit of claim 23, wherein said cartridge comprises a razor head having a shaving aid arranged thereon. 50
